CIRCUIT ARRANGEMENT FOR AN ION RELAY AND A MECHANICAL RELAY

Max Steenbeck, Berlin-Westend, Germany, assignor to Siemens-Schuckertwerke Aktiengesellschaft, Berlin-Siemensstadt, Germany, a corporation of Germany

Application July 11, 1931, Serial No. 550,203,
and in Germany July 15, 1930

2 Claims. (Cl. 250—41.5)

My invention relates to a connection of an ion relay and a mechanical relay.

Ion relays have, as is well known, on the one hand the great advantage of being highly sensitive and extremely rapidly responsive, but on the other hand the serious disadvantage of having a comparatively short life. The object of the present invention is to lengthen the life of ion relays in most of the fields of application without lessening the favorable properties of these relays in the arrangement or by the method of connection. In most cases in which glow relays may be used it is only necessary to give or to initiate the desired switching impulse by means of the glow relay. When this switching impulse has been imparted, the glow relay may be extinguished through any kind of arrangement of mechanical or other relays. In most prior art relay circuits the glow relay is located at the places where otherwise a mechanical relay might be located. This manner of employment of the glow relay does not, however, take its particular properties into account. In the case of a mechanical relay, it is in most cases immaterial for the length of its life, whether the relay is used for the greater part of the time in a closed or an open position. The wear of the mechanical relay occurs substantially only during the actual switching operation. In contrast to the mechanical relay the length of the life of the ion relay is not mainly determined by the number of switching operations, but by the total length of time during which current has passed through the relay. If the ion or glow relay continues to carry current after giving a switching impulse, its life will be unnecessarily shortened without any advantage to the relay circuit.

According to my invention an ion relay and a mechanical relay are so placed in an arrangement that the ion relay carries current only at the moment of the switching action and that during the rest of the time the current passes through a mechanical relay which is switched in by the ion tube and in its turn automatically cuts out or shunts the ion tube.

As an example for the application of my invention, an arrangement is diagrammatically illustrated in the accompanying drawing and described in the following for switching on and off the light automatically in dependence of the intensity of the daylight, e. g. on the disappearance and appearance, respectively, of daylight. Instead of the varying intensity of the daylight,

variations in intensity of artificial sources of light may of course also be used as impulse sources.

In this diagram 1 represents a photo-electric cell, 2 a constant resistor, both connected in series with a source of current 3. Between cell 1 and resistor 2 a shunt connection branches off which contains an ion relay tube 4, and the armature 6 of an electro-mechanical relay comprising the solenoid coils 7 and 8, and the contact element 9 operated by armature 6 for opening and closing the local power circuit 12 which operates the lighting system 11. The armature 6 has two staple resting positions against contacts *a* and *b*, in either of which it remains even if no current flows through solenoid coils 7 or 8. In the position shown the armature rests against contact *a*, where it maintains local power switch 10 closed, so that current is supplied to lighting system 11. With armature 6 on contact *a*, a local circuit is set, which includes ion relay 4 and solenoid coil 7, and which is in shunt with resistance 2. Since day-light is assumed to be absent from cell 1, the normal high resistance of the photo-cell prevents much current from flowing through the cell circuit, and the potential at the ends of the aforementioned shunt circuit is not high enough to cause relay 4 to respond. As soon as sufficient day-light appears and strikes cell 1, the resistance of the latter is materially decreased, and now sufficient local current flows through the cell and ion relay 4 to energize coil 7, whereby armature 6 is thrown to the right against contact *b*. Thus the local lights 11 are extinguished and at the same time a different local circuit is set at contact *b*, which includes coil 8 and ion relay 4, and which is connected in shunt with cell 1. So long as day-light maintains the cell resistance low, the potential difference at the ends of the last-mentioned shunt circuit is not great enough to bring ion relay 4 to the point where it responds, and therefore armature 6 remains on contact *b*. As soon as day-light disappears the resistance of cell 1 materially increases and now the potential at ion relay 4 becomes great enough to cause it to respond, and thus current flows and energizes coil 8, which now throws armature 6 back to the left, thereby relighting the lights 11.

Similar combinations of mechanical relays and glow relays can be employed in almost all cases in which the use of a glow relay is per se desirable but was hitherto not advisable owing to the short life of the gas discharge relay.

Instead of employing one glow tube, it is of course also possible to use two or more glim

tubes or glow tubes having a plurality of electrodes.

I claim as my invention:

1. In a control arrangement for an electric work circuit, an ion relay responsive at a desirable minimum potential, and a double acting electromagnetic relay having an armature for opening and closing the work circuit, and two coils for moving the armature into the work circuit opening and closing position, an armature contact in each of said positions each contact connected respectively with one terminal of one of said coils, one electrode of said ion relay being connected to said armature and the other electrode being connected to the other terminals of said coils, and means for applying to said ion relay and to the coil which happens to be connected to it by its pertaining armature contact, a potential sufficient for the relay response to permit current flow through it and through said connected coil to move the armature to the other armature contact, for interrupting the relay circuit, and for setting the circuit through the other coil.
2. In a control arrangement for an electric work circuit, an ion relay responsive at a desirable minimum potential, and a double acting elec-

tromagnetic relay having an armature for opening and closing the work circuit, and two coils for moving the armature into the work circuit opening and closing position, an armature contact in each of said positions connected respectively with one terminal of said coils, one electrode of said ion relay being connected to said armature, a photo-electric cell connected with the other ion relay electrode and the other terminal of one of said coils, and a resistance also connected with said other ion relay electrode and with the other terminal of the other of said coils, and a source of potential connected in series with said cell and said resistance, for applying, when the cell is light-energized, a potential to said ion relay sufficient for its response to permit current flow through it and through one of said coils to move the armature from one to the other contact to interrupt the relay current and to set the circuit through the other of said coils, by which sufficient potential for response is applied to said ion relay when said photo-cell is deenergized, for moving said armature from said other contact back to the first contact.
